UNITED STATES PATENT OFFICE.

EVERETT K. LEFFINGWELL, OF MONTCLAIR, NEW JERSEY.

DESIGN FOR A JAR OR RECEPTACLE.

SPECIFICATION forming part of Design No. 32,472, dated April 10, 1900.

Application filed February 20, 1900. Serial No. 5,971. Term of patent 14 years.

To all whom it may concern:

Be it known that I, EVERETT K. LEFFINGWELL, a citizen of the United States, residing at Upper Montclair, in the county of Essex and State of New Jersey, have invented a new and original Design for a Jar or Receptacle, of which the following is a specification, reference being had to the accompanying drawings, forming a part thereof.

- 5 o In said drawings, Figure 1 is a side elevation of a receptacle embodying the design, a part of the receptacle being broken away the better to illustrate the design; and Fig. 2 is a plan of the receptacle.
- 5 A is the body portion of the receptacle, and B is the mouth portion thereof.
- a is a reëntering angle extending circumferentially about the mouth portion B below

a conical ring-like bead or band b thereon. Below the angle a is a downwardly-flared 20 conical portion c.

The leading feature of my invention is the reëntering angle a below an overhanging conical or upwardly-tapering bead or band b and the downwardly-flared portion c below 25 said angle.

What I claim is—

The design for a jar or receptacle, substantially as herein shown and described.

In witness whereof I have hereunto signed 30 my name, this 31st day of January, 1900, in the presence of two subscribing witnesses.

EVERETT K. LEFFINGWELL.

Witnesses:

HENRY CONNETT,
PETER A. ROSS.
